UNITED STATES PATENT OFFICE.

JOHN CUOMO, OF NEW YORK, N. Y.

KNITTING DEVICE.

1,309,318.

Specification of Letters Patent.

Patented July 8, 1919.

Application filed October 31, 1918. Serial No. 260,488.

To all whom it may concern:

Be it known that I, JOHN CUOMO, a citizen of Italy, residing at New York city, in the county of New York, State of New York, have invented certain new and useful Improvements in Knitting Devices; and I do hereby declare the following to be a full, clear, and exact description of the invention, such as will enable others skilled in the art to which it appertains to make and use the same.

This invention relates to new and useful improvements in knitting devices, and especially to needle holders.

One object of the present invention is to provide a novel and improved device of this character which is especially adapted for holding the needle on which the material is partially knitted, so that the two hands will be free to manipulate the working needles and the wool or thread.

Another object of the present invention is to provide a novel and improved device wherein the idle needle will be supported on the person of the user in proper position to permit the knitting to be carried out in less time and with less effort.

Other objects and advantages will be apparent from the following description when taken in connection with the accompanying drawing.

In the drawing:

Figure 1 is a perspective view of a needle holding device made in accordance with my invention and showing the same supporting a needle.

Fig. 2 is a reverse perspective view.

Fig. 3 is a vertical longitudinal sectional view taken centrally through the device.

Fig. 4 is a transverse sectional view taken on the line 4—4 of Fig. 1, looking in the direction of the arrows.

Referring to the drawing, 10 represents a tubular member formed of metal or other suitable material and of the desired length and diameter for the purpose intended and having one open and one closed end. Secured to the tubular member 10 so that the latter will conform to its longitudinal axis, is a plate 11, the upper end of which is convexly curved, extends equally at both sides of the member 10 and is disposed in close relation to the open upper end of the mem-

ber 10. The sides of the plate 11 extend convergingly downwardly from the extremities of its upper curved end, to the tubular member 10. Thus there are provided laterally directed rigid wings adjacent the open end of the tubular member.

In each of the wings of the plate there is formed an opening 12 and passed through these openings is a ribbon or other flexible member, arranged to be fastened around the waist of the user, said flexible member being shown at 13. The marginal edges of the plate are rolled to prevent injury to the person. Into the open upper end of the tube is inserted the needle 14 used in knitting, as shown in Fig. 1 of the drawings.

It is well known that when knitting socks, the knitter must hold the needle which supports the knitting while the other or operating needles are applied, thus adding to the tediousness of the knitting operation. Also when knitting with two large needles, the knitter usually holds one of them, the one containing the knitting, under the arm. With the present device, this may be obviated, as the work supporting needle may be held in the member 10 in firm and close relation to the person's body, thus leaving the hands free. Furthermore, the work is supported at the right height with respect to the body and hands of the knitter. It will also be understood and appreciated that the hands are prevented from cramping by reason of the fact that the work-supporting needle is not held in the hands.

In use, it is not always necessary to employ the attaching member 13. The wings 11 are gripped between the arm and the body of the user, when the flexible member 13 is not employed.

What is claimed is:

1. A knitting device including a tubular needle support, open at one end only and having laterally directed rigid wings adjacent its open end.

2. A knitting device including a tubular needle support open at one end only, laterally extending rigid wings directly adjacent the open end of the support and flexible means carried by the wings for detachably securing the support to the person of the knitter.

3. A knitting device including a tubular

member arranged to receive and support the work holding needles, a plate secured to one end of the tubular member and extending laterally therefrom, said plate having openings therein, and a flexible element engaged through said openings and detachably secured around the waist of the person of the knitter.

In testimony whereof, I affix my signature, in the presence of two witnesses.

JOHN CUOMO.
